UNITED STATES PATENT OFFICE.

RALPH TELLER EMERY, OF CLEVELAND, OHIO.

TRUNK-BAND.

1,353,814.

Specification of Letters Patent. Patented Sept. 21, 1920.

Application filed March 13, 1920. Serial No. 335,414.

To all whom it may concern:

Be it known that I, RALPH T. EMERY, a citizen of the United States, and a resident of Cleveland, in the county of Cuyahoga and State of Ohio, have invented a new and Improved Trunk-Band, of which the following is a full, clear, and exact description.

This invention relates to improvements in trunk bands, an object of the invention being to provide an arrangement of bands or straps preferably of bendable metal, although, of course, they may be of other material which can be positioned around a trunk and securely locked in place, and when in such position will operate to strengthen the trunk and prevent injury thereto as well as prevent opening of the trunk by unauthorized persons.

10 A further object is to provide improvements of the character stated, which can be manufactured and sold at a reasonably low price, which will not disfigure the trunk and which will most efficiently perform the 20 functions for which they are intended.

With these and other objects in view the invention consists in certain novel features of construction, and combinations and arrangements of parts, as will be more fully 30 hereinafter described and pointed out in the claim.

In the accompanying drawings—

Figure 1 is a perspective view illustrating my improvements in position on a 35 trunk;

Fig. 2 is a bottom plan view of my improved arrangement of bands;

Fig. 3 is a fragmentary detail view showing the connection between two of the bands 40 crossing each other; and

Fig. 4 is an enlarged view in section on the line 4—4 of Fig. 1.

My improved device comprises preferably four bands 1, 2, 3, and 4. The bands 1, 2 45 are adapted to be positioned transversely around a trunk 5 and the bands 3, 4 are adapted to be positioned longitudinally around the trunk 5. The bands 1, 2 and 3, 4 are parallel to each other with the bands 1, 2 positioned at right angles to the bands 3, 4 and said pairs of bands are spaced apart the desired distance in accordance with the size of the trunk to be secured.

It will be noted particularly by reference 55 to Fig. 2 that while the bands 1, 2 and the bands 3, 4 are parallel to each other, the

ends of the pairs of bands are not in alignment for a reason which will hereinafter appear.

To removably couple the bands 3, 4 to the bands 1, 2, I preferably provide slots 6 in the bands 3, 4 receiving headed rivets 7 fixed to the bands 1, 2 and the slots 6 are made with enlarged ends 8 for the passage of the heads of the rivets 6 to allow the bands to 60 be disconnected so that they can be packed and stored in relatively small space.

The band 1 is provided at one end with a staple 9 and at its other end with a hasp 10. The band 2 is likewise provided at one end 70 with a staple 9 and at its other end with a hasp 10, but the staple and hasp are positioned on the ends of the band 2 opposite to the arrangement of staple and hasp on the band 1. The bands 3, 4 are provided with 75 slots 11 in their ends to receive the staples 9 of the bands 1, 2 when the bands are positioned around the trunk as shown in Fig. 1, and padlocks 12 are positioned through the staples 9 to secure the parts together. 80

The operation is as follows: The crossed bands are located under the trunk 5 and the ends of the bands are then positioned around the ends and sides of the trunk as shown in Fig. 1. To secure the bands around the 85 trunk the ends of the bands 4 are positioned over the staple 9 of band 1 and then the hasp 10 of band 1 is located over the staple 9 and the padlock 12 employed to secure the parts together. The ends of band 3 are positioned over the staple 9 of the band 2 and the hasp 10 on said band 2 is then placed over the staple 9 of the band 2 and secured by its padlock 12. 90

It will thus be noted that the longitudinally positioned bands 3, 4 are locked to the transversely positioned bands 1, 2 so that the cover 13 of the trunk 5 cannot be raised even though its lock 14 be out of order, and furthermore, the trunk will be strengthened 95 against strains and stresses in all directions so as to prevent injury to the trunk by rough handling in transit.

The bands 1, 2, 3, and 4 are preferably of metal and are as light in weight as possible 105 consistent with strength and durability, and while I believe metal would be the preferred material to use, my invention is, of course, not limited to the use of metal as I may employ any other material in the construction of the bands.

Various slight changes might be made in

the general form and arrangement of parts described without departing from the invention, and hence I do not limit myself to the precise details set forth, but consider 5 myself at liberty to make such changes and alterations as fairly fall within the spirit and scope of the appended claim.

I claim:

A device of the character described, comprising two pairs of parallel bands, said 10 pairs of bands disposed at right angles to each other, both members of one pair of

bands being removably connected to both members of the other pair of bands at their intermediate portion, staples and hasps on 15 the opposite ends of one pair of bands, the other pair of bands having slots in their ends to receive the staples, and the ends of the bands having slots adapted to be locked between the ends of the bands having staples 20 and hasps adjacent oppositely disposed corners on the upper side of the trunk.

RALPH TELLER EMERY.
